BASEBALL BASE

George H. Conrad, Great Bend, Pa.

Application April 1, 1937, Serial No. 134,412

3 Claims. (Cl. 273—25)

This invention relates to improvements in baseball bases.

The object of this invention is to produce a base that will eliminate all of the objectionable features of the type base now in common use, and at the same time will provide a base that will be more durable and safer for use.

One of the objects of this invention is to substitute a rubber casing for the canvas casing now used, and to provide a relatively thick covering of sponge rubber to protect the casing from being cut by the spikes worn on the shoes of the players.

Another object of the invention is to provide means whereby the casing will assume an inflated condition when not bearing any weight so that the continual use of the base will not destroy its shape.

A further object of the invention is to provide a base that will not be cut by the spikes of the players so that those stepping upon the base will not be in constant danger of having their spikes become entangled in the covering resulting in possible injury to the player.

Other objects and advantages of the invention will become apparent from the specification of which the drawing is a part, and wherein:—

Figure 1 is a top plan view of the base;

Figure 2 is a side elevational view of the same;

Figure 3 is a sectional view in elevation on line 3—3 of Figure 1, the strap and stake being shown in elevation;

Figure 4 is a sectional view in elevation on the line 4—4 of Figure 1, and

Figure 5 is an elevational view of the stake on line 5—5 of Figure 3.

Referring more particularly to the drawing wherein like reference characters designate like or corresponding parts in the different views, the casing 10 is preferably made of rubber and comprises a top, bottom, and side walls 11, 12, and 13 respectively. The casing 10 contains a filling material 14 such as hair or the like. The side walls 13 are provided with openings 15 in which are mounted eyelets 16 forming air passages.

A sponge rubber cover 17 having downturned sides 18 is secured to the top 11 and the upper portions of the sides 13 of the casing 10. The cover 17 is adapted to protect the casing 10 from

being cut by the spikes worn on the shoes of the players.

A strap 19 provided with a buckle 20 is adapted to encircle the casing 10 and cover 17. The cover 17 is countersunk at 21 to receive the strap 19 so that it will not project above the cover 17. The side walls 13 are provided with recessed portions 22 to accommodate strap 19.

The bottom 12 has loops 23 formed integral therewith through which strap 19 is passed. Strap 19 is adapted to mount one or more eye-bolts 24 having a pointed end 25 to be driven into the ground to secure the base in position.

There is sufficient packing 14 to cause the casing 10 to expand, creating a vacuum which causes the air to enter through eyelets 16. When the casing 10 is compressed by the weight of a player this air will be exhausted through eyelets 16. In this way the base will always assume its normal expanded condition after weight is removed from it. As a result continual use will not cause the base to lose its shape.

It is to be understood that only the preferred embodiment of the invention has been illustrated, the right being reserved to make such changes and modifications as will not depart from the spirit and scope of the invention.

I claim as my invention:—

1. A baseball base, comprising a rubber casing containing a filling material and being provided with air passages, a soft rubber covering secured to the upper portion of said casing and adapted to protect the casing.

2. A baseball base comprising, a casing provided with air passages, said casing adapted to contain a filling material, a protective covering of sponge rubber secured to the upper portion of said casing, and said casing adapted to be normally distended by the filling material to cause a vacuum to draw the air through said passages into said casing.

3. A baseball base comprising, a rubber casing provided with air passages, said casing containing a filling material, a protective covering of sponge rubber secured to the upper portion of said casing, a strap adapted to encircle the base and to engage loops on the under side of said casing, and said strap adapted to carry driven fastenings to secure said base in position.

GEORGE H. CONRAD. 50
